(57) **CLAIM**

The ornamental design for a hat, as shown and described.

DESCRIPTION

FIG. 1 is a rear elevation view of a first embodiment of a hat in accordance with my design, shown on a person's head.

FIG. 2 is a left side elevation view of a first embodiment of a hat in accordance with my design;

FIG. 3 is a right side elevation view of a first embodiment of a hat in accordance with my design;

FIG. 4 is a rear elevation view of a first embodiment of a hat in accordance with my design,

FIG. 5 is a front elevation view of a first embodiment of a hat in accordance with my design;

FIG. 6 is a top plan view of a first embodiment of a hat in accordance with my design;

FIG. 7 is a bottom plan view of a first embodiment of a hat in accordance with my design;

FIG. 8 is a rear elevation view of a second embodiment of a hat in accordance with my design, shown on a person's head;

FIG. 9 is a left side elevation view of a second embodiment of a hat in accordance with my design,

FIG. 10 is a right side elevation view of a second embodiment of a hat in accordance with my design,

FIG. 11 is a rear elevation view of a second embodiment of a hat in accordance with my design;

FIG. 12 is a front elevation view of a second embodiment of a hat in accordance with my design;

FIG. 13 is a top plan view of a second embodiment of a hat in accordance with my design; and,

FIG. 14 is a bottom plan view of a second embodiment of a hat in accordance with my design.

The partial human figure shown in broken lines in the drawings is included to show the environment in which the design is used, illustrating how the design appears when worn; it forms not part of the claim. The features shown in broken lines form no part of the claimed design.
